[57] CLAIM

The ornamental design for a utility cart, as shown and described.

DESCRIPTION

FIG. 1 is a perspective view of a utility cart showing my new design;

FIG. 2 is a front elevational view thereof;

FIG. 3 is a side elevational view, the other side being a mirror image thereof;

FIG. 4 is a rear elevational view;

FIG. 5 is a top plan view;

FIG. 6 is a bottom plan view;

FIG. 7 is a perspective view similar to FIG. 1 except for the angle of perspective, but showing a portion of the cart being moved into an operative position;

FIG. 8 is a side elevational view of the cart as shown in FIG. 7;

FIG. 9 is a top plan view of the cart shown in FIG. 7;

FIG. 10 is a front elevational view of the cart shown in FIG. 7;

FIG. 11 is a rear elevational view of the cart shown in FIG. 7; and,

FIG. 12 is a bottom plan view of the cart shown in FIG. 7.
